UNITED STATES PATENT OFFICE.

BURNAM R. CLARK, OF UNION GROVE, WISCONSIN.

VICE.

SPECIFICATION forming part of Letters Patent No. 378,082, dated February 21, 1888.

Application filed May 2, 1887. Serial No. 236,785. (No model.)

To all whom it may concern:

Be it known that I, BURNAM R. CLARK, of Union Grove, in county of Racine and State of Wisconsin, have invented new and useful 5 Improvements in Vises for Wood-Workers; and I do hereby declare the following to be a full, clear, and exact description of said invention, reference being had to the accompanying drawings, and to the letters or figures 10 of reference marked thereon, which form a part of this specification.

My invention, to be hereinafter distinctly claimed, consists in the form, construction, and combination of the various parts of the 15 device hereinafter described.

In the drawings, Figure 1 is a vertical cross-section of a part of a carpenter's bench with my improved device in connection therewith. Fig. 2 is an inner view of my device separated 20 from the bench and as seen at right angles to the view in Fig. 1. Fig. 3 is a perspective view of parts of my device. Fig. 4 is a detail.

In the drawings, A is the leg of a carpenter's bench.

25 B is a board forming the side of the bench, and B' is a board forming the top of the bench, and B" is a cross beam or support.

A bracket or plate, C, is affixed to the inside of the leg A by bolts S S. Integral with 30 the plate C is an inwardly-projecting sleeve, D. An aperture through the plate C, continuing lengthwise through the sleeve D, is adapted to receive and carry horizontally the traveling arm E. This traveling arm E, for greater 35 strength and adaptability for carrying its end load in a true line, is preferably constructed with a flat upper part, E', oblong, horizontally crosswise, with a centrally downward-projecting rib, E", longitudinally. At its 40 outer end this traveling arm E is provided with a plate, F, either integral therewith or rigidly affixed thereto, which plate F extends at right angles to the arm E, and is mostly above the arm. This plate F is provided on 45 its upwardly-extending edges with outwardly-projecting flanges F' F".

The plate C, sleeve D, arm E, and plate F are preferably constructed of malleable iron. A wooden jaw, G, provided with recesses G', 50 adapted to receive snugly therein the flanges F' F", is secured rigidly by bolts H H to the

plate F. This jaw G terminates at its upper extremity in a curved rounded outer edge, I, for convenience and adaptability for use.

The jaw G forms one side of the vise, the 55 board B of the bench forming the other or opposing jaw or resisting support. The top of the jaw G is located at the same height as the top of the bench, and the inner face of the jaw G is opposite to the board B.

60 The material held by this device for wood-workers' work is held between the upper end of the jaw G and the board B; and for wood-workers' use, on account of the possibility and even liability of his sharp tools coming in 65 contact with the upper end of this jaw, it is considered necessary to have the upper end of the jaw of the vise constructed of wood. It is with reference to this supposed absolute requirement in the construction of wood-work- 70 ers' vises that the peculiar form and construction of the parts of this jaw and the plate F to which it is affixed have been devised. This jaw is intended and adapted to move forward and backward toward and from the bench in 75 a right line thereto, the inner face of the jaw G being constantly parallel with the outer surface of the bench or board B. The jaw G is moved toward and from the bench by means of the iron screw K, which passes through an 80 aperture therefor in the jaw G and turns in a nut, L, secured in the plate C. An iron collar, M, rests against and is secured to the outer surface of the jaw G, about the aperture 85 through which the screw K passes. The aperture through the collar M is only large enough to allow the tang of the screw to pass through it, and the end of the screw proper bears against the collar M on its inside, while the cross-head N, in which the tang of the screw is received 90 and held rigidly, bears against the collar on the outside, whereby the screw is held against any endwise movement in the jaw G, while rotating freely therein, and whereby, as the screw travels forward and back in the leg A, 95 the jaw G is carried forward and back with the screw. At its outer end the screw K is provided with a lever or crank-arm, O. The nut L enters an aperture therefor in the plate C, and is retained in position by a shoulder, P, 100 on its outer perimeter, which bears against the outer surface of the plate C, and by a feather,

Q, integral therewith, which enters a recess therefor in the plate C, the shoulder P being adapted to prohibit the nut from entering farther into the plate C, and the feather Q being adapted to prohibit the nut from rotating in the plate.

What I claim as new, and desire to secure by Letters Patent, is—

1. In a wood-worker's vise, the wooden-faced jaw G, affixed to the plate F, and the traveling arm E, rigidly affixed to the plate F, in combination with a bench provided with a plate, C, in which the arm E is adapted to travel, and the screw K, adapted to move the jaw G toward and from the bench, substantially as described.

2. In a wood-worker's vise, the wooden-faced jaw G, with recesses G' G', in combina-

tion with the plate F, provided with flanges F' F', adapted to enter recesses G' G', and the traveling arm E, rigidly affixed to the plate F, all substantially as described.

3. In a wood-worker's vise, a bench provided with a leg, A, the thereto rigidly-attached plate C, provided with sleeve D, in combination with the traveling arm E, secured to the jaw G, a jaw, G, and a screw, K, adapted for moving the jaw G, substantially as described.

In testimony whereof I affix my signature in presence of two witnesses.

BURNAM R. CLARK.
